UNITED STATES PATENT OFFICE.

CHARLES A. HASCALL, OF PORTAGE, WISCONSIN.

SHIRT.

SPECIFICATION forming part of Letters Patent No. 499,788, dated June 20, 1893.

Application filed October 12, 1892. Serial No. 448,638. (No model.)

To all whom it may concern:

Be it known that I, CHARLES A. HASCALL, a citizen of the United States, residing at Portage, in the county of Columbia and State of Wisconsin, have invented certain new and useful Improvements in Shirts, of which the following is so full, clear, and exact a description as will enable others skilled in the art to which it appertains to make and use the same.

In the accompanying drawing the figure represents a front elevation of the shirt with the upper portion of one of the flaps turned back.

The object of my invention is to provide a shirt which will secure to the wearer, the greatest convenience, comfort, and service, at the least expense of material, and of physical and mechanical force.

In the accompanying drawing A designates the main shirt body, which for convenience, I have shown open in front from top to bottom. The outer flap B, is provided with a series of button holes a, a, down the edge; and at the beginning of the flap at the waist is a single button hole C, in practice from four to six inches back of the edge of the flap. The opposite flap D, is adapted to lap beneath the flap containing the button holes, and is provided with a row of buttons E, and a single button F, at the edge of the flap. The under flap D is tapered in outline from the upper neck band portion down to the point where the single button hole C goes over the single button F thus leaving a continuous strip of material tapered in outline from the button F to the neck band. The flap from this point down is straight, thus forming a double breasted flap from the point where the lower buttons and button holes occur to the bottom.

This style of shirt is adapted for use to go under the straight edge from the collar to the bottom and also the part connected to the flap from the collar button to the place where it buttons at the notch.

It is obvious that various forms of fastenings may be used for the lap, such as buckles, strings, hooks and eyes, or other equivalent fastening devices, well known to the trade. By the use of a shirt of this pattern, a very slender or a very portly person may be fitted

perfectly, which is a great desideratum in the manufacture of such articles of wearing apparel.

The improvement is clearly adapted for use with every form of shirt, ladies' and gentlemen's vests, &c.

In practice I may use button holes alone in the shirt and the fastening can then be effected by the use of ordinary collar buttons.

I am aware that it is old to construct wearing apparel double-breasted and to over-lap one flap with the other. I am not aware, however, of a shirt ever having been made which consisted in a main body having one flap provided with a vertical row of fastening devices such as buttons and button holes and the flap made tapering in outline and extending in an oblique line from the center of the collar down and across the front to the opposite side of the wearer, when the shirt is in position on the wearer, and then having the skirt extending down in a vertical line and at the junction of the vertical line and the oblique line, having a fastening device as a button hole, and having the opposite side provided with a button fastening adapted to register with the single fastening at the junction of the vertical and oblique lines of the first flap and a vertical row of fastenings adapted to register with the vertical row of fastenings on the first flap.

I do not wish to be understood as limiting myself to the exact outlines shown, but

What I wish to claim and cover broadly, and what I wish to secure by Letters Patent of the United States, is—

A shirt opening in front, having flaps provided with fastening devices, the flaps of the shirt adapted to over-lap at the skirt and one of the flaps made tapering from the collar portion to the skirt and provided with a fastening device at the edge of the meeting lines of the upper end of the vertical portion of the skirt and the lower end of the oblique line extending from the collar to the skirt and also provided with a row of fastening devices back of the edge of the flap and the opposite flap provided with a row of fastening devices to register with the row of fastening devices of the first flap and an independent fastening

adapted for engagement with the fastening at the junction of the vertical line and the oblique line on the first flap, all constructed substantially as described and constituting a shirt double at the flap in front only and forming a practically single breasted shirt as set forth.

In testimony whereof I affix my signature in the presence of two witnesses.

CHARLES A. HASCALL.

Witnesses:

L. MCNEEL,
J. H. NEWELL.
